BOTTLE

Howard Cooper, 175 E. Delaware, Suite 7707,
Chicago, Ill. 60611

Filed Nov. 18, 1971, Ser. No. 200,280

Term of patent 14 years

Int. Cl. D9—01

U.S. Cl. D9—28

FIG. 1 is a front view of a bottle embodying my new design;

FIG. 2 is a top view thereof; and

FIG. 3 is an enlarged cross-sectional view of a portion of the bottle shown in FIG. 1 taken along the line 3—3 thereof.

The back of the bottle is identical to the front view shown in FIG. 1.

I claim:

The ornamental design for a bottle, substantially as shown and described.
